UNITED STATES PATENT OFFICE.

ROBERT B. WATSON AND JESSE C. KITTERMAN, OF CORYDON, INDIANA.

FLY-EXIT FOR SCREEN DOORS AND WINDOWS.

1,343,069.

Specification of Letters Patent. Patented June 8, 1920.

Application filed December 2, 1919. Serial No. 341,997.

To all whom it may concern:

Be it known that we, ROBERT B. WATSON and JESSE C. KITTERMAN, citizens of the United States, residing at Corydon, in the 5 county of Harrison, State of Indiana, have invented certain new and useful Improvements in Fly-Exits for Screen Doors and Windows; and we do hereby declare the following to be a full, clear, and exact description of the invention, such as will enable others skilled in the art to which it appertains to make and use the same.

This invention relates to new and useful improvements in window and door screens, 15 and particularly to fly exits therefor.

One object of the present invention is to provide a novel and improved fly exit attachment for a screen door or window whereby the flies will be permitted to readily 20 pass out.

Another object is to so arrange the exit that the natural tendency of the fly to crawl to the upper end of the door or window to escape is taken advantage of.

25 Another object of the present invention is to provide a novel and improved device of this character which is an improvement on our former Patent #1,314,774, issued September 2, 1919, in the names of Robert B. Watson and Jesse C. Kitterman.

Other objects and advantages will be apparent from the following description when taken in connection with the accompanying drawing.

30 In the drawing:

Figure 1 is an elevation of the outside of a screen door made in accordance with our invention, showing the improved exits for the flies.

40 Fig. 2 is an elevation of the inside of the screen door.

Fig. 3 is an enlarged vertical sectional view taken on the line 3-3 of Fig. 2, through one of the exit compartments and 45 the corresponding exit notch in the upper strip of the door frame.

Referring particularly to the accompanying drawing, there is shown a portion of a screen door which includes the sides 10 and 50 the upper cross strip 11. Secured to the outer face of the sides and upper strip of the door is the wire screen 12, the same being covered, at its marginal edges with the usual molding strips 13. Formed 55 through the lower edge of the strip 11 of

the door frame are the notches or recesses 11', the same opening through both the inner and outer faces of the strip, and being disposed above the upper marginal edge of the screen 12, as shown in Fig. 1. To the 60 upper portions of the inner faces of the side strips 10 and to the corresponding face of the upper strip 11, is a piece of screen 14, the upper edge of which is disposed above the upper portions of the recesses and 65 the lower edge being disposed a suitable distance downwardly from said strip. Molding strips 15 bind this screen 14 to the door frame. Disposed between the screens 12 and 14 is a strip of wire screen 16 whose 70 side edges abut against the faces of the said screens, said screen strip being bent in a zig-zag fashion, and having the junctions of the inclined portions, shown at 17, arcuate and disposed within the recesses, as 75 clearly seen in Fig. 1. The opposite ends of the strip 16 are secured to the inner side faces of the side strips 10 of the door frame, whereby a number of upwardly tapering compartments are formed into which 80 the flies crawl in their travel toward the upper end of the door. By reason of the fact that the arcuate portions 17 are disposed in the recesses 11', and the fact that the upper edge of the screen 14 is below the 85 recesses, permits the outer ends of said arcuate portions to be open to the outside whereby the flies can easily pass out from between said screens. The screen 12 effectively closes the inner ends of the arcuate 90 portions 17 so that the flies must pass outwardly.

It will be noted that the binding molding strip 15 which extends horizontally across the door, below the openings or recesses, 95 are in the plane of the outer screen so that the flies walk from this screen onto the strip and fly outwardly therefrom, to the outside air.

While we have shown the exit as applied 100 to a screen door we wish it understood that the same may be as easily and effectively applied to a window screen.

What is claimed is:

A fly exit comprising a frame having 105 side and top portions, the top portion being formed with transverse open ended recesses in the lower face thereof, wire screen secured to the outer face of the screen with its upper edge covering one end of each of the 110

5 recesses, a screen secured to the other face of the frame and having its upper edge disposed below the recesses whereby said recesses are open thereat, and fly passages between the screens and extending into the recesses and formed with transverse passages closed at one end by the first screen and open at the other ends.

In testimony whereof, we affix our signatures, in the presence of two witnesses.

ROBERT B. WATSON.
JESSE C. KITTERMAN.

Witnesses.
